(57) **CLAIM**

The ornamental design for a multi-sided container as shown and described.

DESCRIPTION

FIG. 1 is a top perspective view of a multi-sided container of the present invention showing our new design;

FIG. 2 is a bottom perspective view thereof;

FIG. 3 is a top plan view thereof;

FIG. 4 is a bottom plan view thereof;

FIG. 5 is a first elevational view thereof;

FIG. 6 is a second elevational view thereof;

FIG. 7 is a third elevational view thereof;

FIG. 8 is a fourth elevational view thereof;

FIG. 9 is a fifth elevational view thereof;

FIG. 10 is a top perspective view of another embodiment of a multi-sided container of the present invention showing our new design;

FIG. 11 is a bottom perspective view thereof;

FIG. 12 is a top plan view thereof;

FIG. 13 is a bottom plan view thereof;

FIG. 14 is a first elevational view thereof;

FIG. 15 is a second elevational view thereof;

FIG. 16 is a third elevational view thereof;

FIG. 17 is a fourth elevational view thereof;

FIG. 18 is a fifth elevational view thereof;

FIG. 19 is a top perspective view of another embodiment of a multi-sided container of the present invention showing our new design;

FIG. 20 is a bottom perspective view thereof;

FIG. 21 is a top plan view thereof;

FIG. 22 is a bottom plan view thereof;

FIG. 23 is a first elevational view thereof;

FIG. 24 is a second elevational view thereof;

FIG. 25 is a third elevational view thereof;

FIG. 26 is a fourth elevational view thereof; and,

FIG. 27 is a fifth elevational view thereof.

(Continued)

The broken lines shown in the drawings depict portions of the multi-sided container that form no part of the claimed design.
